ELECTRICAL RESISTANCE UNIT

David T. Siegel, Chicago, Ill.

Application March 24, 1930, Serial No. 438,605

5 Claims. (Cl. 201—63)

This invention relates to improvements in electrical resistance units.

An electrical resistance unit usually consists of a wire having a desired temperature coefficient wound on a tube or base, preferably of porcelain, fitted with suitable terminals and surrounded by a suitable covering. The wire is wound around the tube or base either contiguously or at desired spaced intervals. This wire is very thin, usually below No. 40 B & S gauge. This wire is so thin and fine that it has little, if any physical, strength or resistance. The covering applied to a resistance unit is normally enamel which is fired on to the porcelain tube at a high temperature.

15 The coefficient of expansion of the terminals made of copper or other suitable material is comparatively much greater than the coefficient of expansion of the porcelain tube, and similarly, upon cooling, the contraction of the terminal is likewise far greater. Consequently upon cooling the fine, thin resistance wire, at the point where the same contacts with the terminal, will have exerted against it by reason of the contraction of the copper terminal a pressure or pull far beyond any physical resistance inherent in said thin wire, and the part of the wire adjacent to the terminal lying upon or contacting with the porcelain will be subjected to a strain or pull because of the comparative lack of any contraction of the porcelain tube.

25 The result has been that upon contraction, the pull or pressure exerted by the copper terminal against the thin resistance wire has caused the latter to break or be snapped off, with the consequent result that such resistance unit is wholly defective and worthless. The commercial loss entailed by such breaking of the resistance wire has heretofore been a serious commercial problem.

It is therefore the object of my invention to 40 produce an electrical resistance unit of practical and commercial use and value in which the breaking or severing of the resistance wire is eradicated or practically eliminated without in any manner detracting from the utility of a resistance unit and without changing or effecting its appearance.

It will be understood that electrical resistance units are made in a great variety of types and sizes, but the invention as herein set forth is obviously applicable to any type and any size, and I therefore do not limit myself to any particular type or size of electrical resistance units.

In my preferred form I use a wire of very low temperature coefficient, which is wound around a 55 refractory porcelain tube fitted with suitable ter-

minals, to which terminals the wire is connected, and such porcelain tube having the wire wound around the same I cover with hard vitreous enamel which is fired on at high temperatures.

At or near each terminal a comparatively heavy 60 wire, about a No. 30 B & S gauge, is wrapped around the porcelain tube upon the fine resistance coil wire. This second wire is not designed to form any part of the resistance circuit but it serves to impart physical resistance and strength 65 to the thin wire upon which it is wound so as to overcome the pull exerted by the terminal upon contraction, with the result that that side of the terminal nearest to the wire remains upon contraction practically fixed, the contraction of said 70 terminal and any moving of said terminal on the porcelain tube taking place at the side remote from the resistance wire. The result is that upon contraction the thin resistance coil proper is not snapped off or broken, with the resulting saving 75 of great loss and expense due to the elimination of ruined resistance units.

It will be understood that the aforesaid construction may be applied to similar parts of each end of the resistance unit, or at any point where 80 contact between the fine wire and a terminal is made.

Other objects of the invention will appear from the following description, directed to the preferred embodiments of the invention, as shown in 85 the drawing forming a part of the specification, the novel features of which are set forth in the appended claims.

In the said drawing,

Fig. 1 is a complete finished electrical resistance 90 unit.

Fig. 2 is a similar view as Fig. 1 prior to the application of the covering of vitreous enamel or other suitable coating.

Fig. 3 is an enlarged end view broken away 95 of the electrical resistance unit of Fig. 2.

Fig. 4 is a cross-sectional view taken on the line 4—4 of Fig. 3.

Fig. 5 is a view of a large size of electrical resistance unit prior to the application of vitreous 100 enamel or other suitable covering having terminals of phosphor bronze leads.

Like reference characters are applied to like parts in the various figures.

The reference character 1 designates the copper terminals on the resistance unit, in which are provided suitable holes 2 for forming contact. The resistance unit is covered with a coating 3 preferably made of vitreous enamel which is fired on to the resistance coil at a high temperature, 110

the ends of the porcelain tube upon which the resistance coil is wound being designated by reference character 4.

The thin wire forming the resistance coil 5 is shown in Fig. 2. This coil 5, obviously, is not shown in Fig. 1, since it is beneath the coating 3. Reference character 6 designates the comparatively heavy wire wound at or near the terminals at each end of the resistance unit, and 7 indicates the end of the wire 6 leading to and connected with a prong on the copper terminal 1. Reference character 9 designates the end of the resistance coil proper, 5 forming a contact and completing the circuit with the copper terminals 15 at 8. 10 represents the hollow portion of the porcelain tube and 11 represents a part of the porcelain tube 4. 12 represents a flexible terminal of phosphor bronze or other suitable material. 13 represents a wire used to hold the flexible terminals in place.

It will be understood that various changes may be made in form and size and in the application thereto of my invention without departing from the principle and spirit of the same.

Having thus described my invention, what I claim as new and desire to secure by Letters Patent is:

1. An electrical resistance unit comprising a tube of refractory material, a fine resistance wire wound about the tube, terminals fitted directly on the tube and abutting with the end strand of the resistance wire, and a reinforcing wire en-

veloping the resistance wire adjacent the terminals.

2. An electrical resistance unit comprising a tube of refractory material, a fine resistance wire wound about the tube, terminals fitted directly on the tube and abutting with the end strand of the resistance wire, a reinforcing means superposed upon the resistance wire adjacent the terminals, and a covering material for the resistance wire.

3. An electrical resistance unit comprising a tube of refractory material, a fine resistance wire wound about the tube, terminals fitted directly on the tube and abutting with the end strand of the resistance wire, a reinforcing wire enveloping the resistance wire adjacent the terminals, and a covering material for the resistance wire.

4. The method of making an electrical resistance unit comprising winding a fine resistance wire upon a tube of refractory material, fixing terminals on the tube to receive the ends of the resistance wire, covering the resistance wire adjacent the terminals with reinforcing material, and coating the unit with a covering material.

5. The method of making an electrical resistance unit comprising winding a fine resistance wire upon a tube of refractory material, fixing terminals on the tube to receive the ends of the resistance wire, covering the resistance wire adjacent the terminals with a winding of heavier wire, and coating the unit with a covering material.
